UNITED STATES PATENT OFFICE.

RALPH ROY BELCHER, OF BAINBRIDGE, GEORGIA.

STORE-SHELVING.

1,246,844.

Specification of Letters Patent. Patented Nov. 20, 1917.

Application filed September 15, 1915. Serial No. 50,835.

To all whom it may concern:

Be it known that I, RALPH ROY BELCHER, a citizen of the United States, residing at Bainbridge, in the county of Decatur and 5 State of Georgia, have invented new and useful Improvements in Store-Shelving, of which the following is a specification.

The present invention relates to store shelving, and has for its object to provide 10 a light, easily assembled shelf structure which may be conveniently erected either against the wall of a store or, if desired, in mid-floor position, provision being made whereby the necessary rigidity in structure 15 and stability will be secured regardless of the particular location of the shelving, whether against the wall or in mid-floor position.

In the drawings which accompany and 20 form a part of this disclosure, I have shown one embodiment of my invention, but the disclosure is illustrative only and in no sense restrictive of the invention, as it is obvious that changes may be made within 25 the skill of the mechanic without departing from the principles of my invention.

In said drawings,—

Figure 1 is a perspective view showing my improved shelving.

30 Fig. 2 is a view partly in section to show the engagement of the uprights and the shelf supports.

Fig. 3 is a perspective view of the bracket for the shelf support.

35 Fig. 4 is a perspective view of a shelf support.

Figs. 5 and 6 are detailed sectional views to show the shelving and shelf support.

Referring to the drawings by numerals, 40 like numbers indicating like parts in the several views, 10 denote the uprights which are utilized in my construction, these uprights being formed of metal bars of suitable gage, and in the particular form shown 45 herein the bars are L-shaped in cross section, although, obviously, the matter of the cross section of the bars is not material, although by using an L-shaped bar, or at least bars having angularly disposed webs 50 or flanges, a very rigid upright of comparatively light metal may be secured.

The bars composing the uprights 10 are slightly spaced, as shown, to receive bracket arms 11, which bracket arms and the two 55 members of the uprights are fastened together by through bolts or rivets 12, these

brackets 11 being spaced from one another to give the required shelf spacing, and if desired the uprights may be drilled at different points, so as to permit adjustment of 60 the brackets vertically to provide for variation in shelf spacing.

The brackets 11 which are preferably cast, although they may be forged or formed in any desired manner, are provided with 65 vertically disposed ribs 14, which, when the bracket 11 is slipped into place between the members of the uprights 10, will take a firm bearing against the edges of the uprights, and when the bolts or rivets 12 are tightened 70 insure the maintenance of the bracket in an immovable horizontal position.

75 Preferably, the rear or entering end of the bracket 11 will depend, as shown, so that such depending end will lie close to the next bracket below, and a projection 15 will be formed at this depending end against which the rear end of the shelf support 16 will bear, as shown in Fig. 2 when such shelf support is in place.

80 The shelf supports 16 are removably mounted on the supporting brackets and are preferably formed, as shown, of T-shaped angle iron, the T-flange being removed at the rear end of the support 16 so that the 85 vertical web of the support 16 may be entered between the members of the uprights 10 and be supported thereby with the rear end of the shelf support 16 bearing against the projection 15 so as to 90 maintain it in horizontal position. The support 16 will rest upon the bracket 11, and in order to prevent displacement of the support I preferably provide a notch 17 in the web of the support, which notch is engaged by a nose or projection 18 at the forward end of the bracket 11.

95 The supports may be readily engaged and disengaged in the manner shown in Fig. 2 by simply entering the cut-away end of the support between the members of the uprights 10 until it has engaged beneath the projection 15 on the bracket above, whereupon it will be dropped into its horizontal position with the projection 15 on the 100 bracket engaging the notch 17 in the shelf support, there being sufficient clearance between the brackets as mounted in the uprights to permit the shelf supports to be readily put in place and unshipped as desired.

110 The said shelf support 16 has at its for-

ward projecting portion a relatively broad T-head which forms a stable support for the shelving, and in order to secure the shelving in place, and, furthermore, that 5 the shelving may serve as braces for the entire structure, I provide the shelf sections at their ends with dowel pins 19 adapted to enter holes 20 formed in the T-flange of the shelf support 16, the shelf sections 16 being 10 cut to the proper length so that their ends will meet on the T-flange of the shelf supports 16 and the dowel pins 19 engage in the holes 20 in such shelf supports and will not only maintain the shelves in proper position 15 but will serve to give rigidity to the entire structure.

At the lower end of the uprights 10, I provide cross braces 21 which are formed of light metal with their ends bolted or riveted 20 to the uprights at 22, these cross braces at the lower ends of the uprights, together with the shelving 16 which engages by the dowel pins 19 with the holes 20 in the shelf supports 16, serving to very effectively brace 25 the uprights 10 against displacement and giving a very rigid structure. To maintain the structure upright in event of its not being arranged adjacent to and fastened to a wall, I provide the bracing frames 23 which 30 are preferably formed of substantially X-shape, as shown, one leg being fastened by a suitable bolt or rivet to the lower end of the upright, and the other leg having a foot 24 adapted to rest upon the floor at a distance 35 from the upright and be there secured by a screw, or in any other suitable manner, and, if desired, this X-shaped brace may be provided with a shelf support to form a broad working shelf, the shelf 23 resting on 40 top of the X-shaped brace.

With the X-shaped brace attached to the upright and secured to the floor as described, the uprights and shelves will be securely held against tipping or displacement, 45 and the necessity for special settings or foundations for the shelving done away with, as it is obvious it may be erected in any mid-floor space and securely fastened.

It will be obvious that the brackets 50 may be made of any length desired, dependent on the spacing of the shelving. If wide spacing of the shelving vertically is desirable, the bracket will be relatively long, as shown in full lines in Fig. 3, but if the shelving 55 is to be more closely spaced, then as indicated in dotted lines, the bracket will be correspondingly shortened.

I do not limit myself to the exact mechanical details shown, as other expedients within the range of my invention may be adopted without departing from the principles thereof.

What I claim is:—

1. The combination in store shelving, of a 65 plurality of uprights, a shelf support pro-

jecting from each of said uprights at the upper part thereof, a shelf mounted on said supports and coupled therewith to effectively brace said uprights, braces connecting said uprights at the lower part thereof, and braces extending outwardly from each of said supports and adapted to rest upon the floor in advance of said uprights. 70

2. The combination in store shelving, of a plurality of uprights, a shelf support projecting from each of said uprights at the upper part thereof, a shelf mounted on said supports and coupled therewith to effectively brace said uprights, cross-braces connecting said uprights at the lower part thereof, and cross-braces extending outwardly from each of said uprights and each provided with a supporting foot adapted to rest upon the floor in advance of said uprights. 75

3. In a store shelving construction, and in combination, an upright formed of spaced-apart bars, a plurality of brackets mounted between said bars and having projecting wings to abut the front edges of said bars, 90 and shelf supports having reduced rear ends to engage the inter-space between said bars resting upon said brackets. 85

4. In a store shelving construction, and in combination, an upright formed of spaced-apart bars, a plurality of brackets mounted between said bars and having projections at their lower ends, shelf supports having reduced rear ends adapted to be entered between said spaced bars and engage the projection at the lower end of a bracket, and means for locking said shelf supports to said brackets against horizontal movement. 95

5. In store shelving construction, and in combination, an upright formed of spaced-apart bars, a bracket mounted between said bars and having a forwardly projecting supporting member provided with an interlocking projection, a shelf support engaging between said bars and resting upon said bracket, said shelf support having a notch to engage said bracket projection and lock it against horizontal movement. 105

6. In store shelving construction, and in combination, an upright formed of spaced-apart bars, a plurality of brackets mounted between said bars, said brackets being cut-away at their lower ends to form a receiving space for a shelf support and having an abutment to engage a shelf support, and a shelf support adapted to be entered between said bars in the receiving space formed by said bracket and engage the bracket abutment so as to be maintained in fixed horizontal position. 115

7. A bracket for store shelving having a relatively thin top portion adapted to be entered between spaced supporting bars, vertically disposed setting ribs formed on said body portion, a depending abutment at the 120

- lower end of said bracket to engage a shelf support, and a supporting member projecting forwardly from said body portion and having means to interlock with a shelf support.
5. A bracket for store shelving formed of a relatively thin web, setting ribs extending at angles from said web, an abutment projecting from the lower end of said web on one side of said ribs, a shelf supporting member extending on the other side of said ribs, and an interlocking projection on said last-named member adapted to engage with a shelf support.
10. 8. A bracket for store shelving formed of a relatively thin web, setting ribs extending at angles from said web, an abutment projecting from the lower end of said web on one side of said ribs, a shelf supporting member extending on the other side of said ribs, and an interlocking projection on said last-named member adapted to engage with a shelf support.
9. A shelf support for store shelving 15 formed of substantially T-shaped angle iron, said support having the horizontal flange of said iron cut-away throughout a portion of its length, and having a notch to interlock with a complementary projection 20 on a supporting bracket.

In testimony whereof I have hereunto set my hand in presence of two subscribing witnesses.

RALPH ROY BELCHER.
